United States Patent Office

Des. 209,135
Patented Nov. 7, 1967

209,135

VEHICLE

Robert J. Orpana, St. Thomas, Ontario, Canada, assignor
to Clark Equipment Company, a corporation of
Michigan

Filed April 1, 1966, Ser. No. 1,746

Term of patent 14 years

(Cl. D14—3)

FIG.1

FIG.2

FIG. 3

FIG. 4

FIGURE 1 is a top perspective view of a vehicle,
FIGURE 2 is a front perspective view with the broken
lines omitted for clarity,

FIGURE 3 is a side elevational view, and
FIGURE 4 is a rear view.

The side of the vehicle opposite the side shown is a
mirror image.

The dominant features of my design reside in the portions
illustrated in solid lines.

I claim:

The ornamental design for a vehicle, as shown and
described.
